UNITED STATES PATENT OFFICE

JOSHUA COMLY, OF PHILADELPHIA, PENNSYLVANIA.

IMPROVEMENT IN MECHANICAL MOVEMENTS.

Specification forming part of Letters Patent No. **154,844**, dated September 8, 1874; application filed June 27, 1874.

To all whom it may concern:

Be it known that I, JOSHUA COMLY, of Philadelphia, Pennsylvania, have invented a new Mechanical Movement, of which the following is a specification:

The object of my invention is to dispense with gearing usually employed in stone-breaking machines, and other machines which, in their operations, demand the exercise of great power; and this object I attain by the application of the mechanical movement which I will now proceed to describe, reference being had to the accompanying drawing, in which—

Figure 1 is a vertical section, and Fig. 2 a plan view, of the movement as applied to a stone-breaking machine.

A is the frame of the machine, between the opposite sides of which are arranged the two breaking-jaws B and B', the former being fixed, and the latter being connected at its lower end to the frame by a pivot, a, the upper end being connected, by links D and D', to a pin, e, to which is also connected the rocking arm E and the upper end of the connecting-rod F, the lower end of the latter being connected to the pin of a crank, G, on the driving-shaft of the machine. The outer end of the rocking arm E is adapted to and bears in a recess or socket in the fixed jaw B, to which the arm is hinged by a pin, f.

It will be evident that the motion imparted

to the pin e by the crank G must be restricted by the rocking arm E to the segmental line x, and that the movement of this pin e, from its lowermost point t to its highest point y, must insure a more limited movement through the links D and D' to the jaw B' from the radial line w to the radial line v.

It will also be evident that the power exerted by the crank G on the driving-shaft is exerted through such great leverage on the jaw B' as to render the employment of the usual cog-gearing unnecessary.

Although I have described my invention as applied to a stone-breaking machine, the same movement may be adopted in punching, swaging, shearing, and other machines, in a manner which will be readily understood by those familiar with machinery of this class.

I claim as my invention—

A mechanical movement in which are combined a crank, G, connecting-rod F, a rocking arm, E, adapted at its outer end to a fixed bearing, links D, and jaw or lever B', all substantially as described.

In testimony whereof I have signed my name to this specification in the presence of two subscribing witnesses.

JOSHUA COMLY.
